UNITED STATES PATENT OFFICE.

NATHAN H. DAVIS, OF PHILADELPHIA, PENNSYLVANIA, ASSIGNOR OF ONE-
THIRD TO LEWIS C. GRATZ, OF SAME PLACE.

CAR-SPRING.

SPECIFICATION forming part of Letters Patent No. 287,638, dated October 30, 1883.

Application filed June 20, 1883. (No model.)

To all whom it may concern:

Be it known that I, NATHAN H. DAVIS, a citizen of the United States, residing in the city and county of Philadelphia, State of Pennsylvania, have invented a new and useful Improvement in Car-Springs, which improvement is fully set forth in the following specification and accompanying drawings, in which—

Figure 1 is a side elevation of a car-spring embodying my invention. Fig. 2 is a vertical section thereof in line $x x$, Fig. 1. Fig. 3 is a top view thereof. Fig. 4 is a bottom view thereof.

Similar letters of reference indicate corresponding parts in the several figures.

My invention consists of a car-spring formed of tapering coils inclosed one within the other, and of reversed pitch, a recessed base, a separable cup, and a connecting-bolt, as will be hereinafter definitely set forth.

Referring to the drawings, A represents a spring, which is constructed of a bar of metal of tapering form, or form increasing in thickness from beginning to end, the same being coiled, whereby the greatest thickness of the spring is at the bottom, the thin part being consequently at top, or vice versa.

The spring as thus constructed is fitted between the base B and follower B', and retained in position by a bolt, C, whose head occupies the socket D, which depends centrally from the follower, and whose threaded end engages with a nut, E, which occupies a recess on the lower face of the base. Within the spring A is inclosed a spring of similar tapering construction, the coil or pitch thereof being in reverse order.

It will be seen that owing to the formation of the spring A the same has resiliency of different degrees, so that when the load is normal the lighter parts of the spring are in service, and as the load increases the stronger parts of the spring are gradually brought into service, whereby the spring is adapted for both light and heavy loads and possesses easy-riding qualities.

Owing to the employment of the two tapering springs coiled in reverse order and inclosed one within the other, a powerful, easy-riding, uniform, and well-steadied spring is produced, this provision obviating the employment of an exterior wall and an interior guide.

The socket or cup D is extended above the top plate or follower, and thus adapted to enter an opening in the bolster, thus serving to connect the bolster and spring and prevent the latter from shifting. The cup D is also made separate from the follower, and has angular sides, as shown by the dotted lines, Fig. 6c 3, and sets in an angular opening centrally in the follower, so as to be prevented from rotating. The opening of the cup is also angular, and the head of the bolt C coincides therewith, by which provision the bolt and cup are prevented from turning, the opening in the bottom recess being also angular to accord with the nut E, (see Fig. 4,) whereby the nut is prevented from turning, the bolt thus always retaining its position, connecting the base 7c and follower.

Having thus described my invention, what I claim as new, and desire to secure by Letters Patent, is—

1. A spring formed of a coil tapering from end to end, in combination with an inclosed spring formed of a coil tapering from end to end, and a base, follower, and connecting-bolt, the coils of the spring being in reverse order, substantially as and for the purpose set forth. 8c

2. A spring formed of a coil tapering from end to end, an inclosed coil tapering from end to end, the coils being of reversed pitch, a recessed base, a follower with a central opening, a separable cup non-rotatingly fitted in said opening, and a non-rotating bolt and nut, combined and operating substantially as and for the purpose set forth.

N. H. DAVIS.
